PHILETUS W. GATES, OF CHICAGO, ILLINOIS, ASSIGNOR TO MUMFORD MOLDING MACHINE COMPANY, OF JERSEY CITY, NEW JERSEY, A CORPORATION.

COMPOUND JOLT-RAMMING MACHINE.

1,306,425.

Specification of Letters Patent. Patented June 10, 1919.

Application filed August 21, 1916. Serial No. 116,020.

To all whom it may concern:

Be it known that I, PHILETUS W. GATES, a citizen of United States, residing at Chicago, in the county of Cook and State of Illinois, have invented certain new and useful Improvements in Compound Jolt-Ramming Machines, of which the following is a specification.

This invention relates to improvements in compound jolt ramming machines and has for its object to provide mechanism of this nature which will permit the operative coupling up of a plurality of small capacity units in such wise as to permit their handling heavy and large work. Hitherto in jolt ramming, it has been customary to construct machines according to the work which they were required to perform and owing to the great weight of such machines when constructed for large work, their operation was highly inefficient unless utilized for the special work for which they were designed. My invention aims to provide means which will permit the coupling up of machines designed and constructed for relatively small work, such machines when so coupled being capable of handling relatively large work.

Still another object resides in the controlling means for such compound multiple unit machines. These and other objects will be more fully set forth and described in the following specification, and shown in the accompanying drawings, in which—

Figure 1 is a plan view showing the arrangement of the operating fluid outlets.

Fig. 2 is a similar view showing the operating fluid inlets, the outlets and cross-bars being shown as removed for clearness.

Fig. 3 is a side elevation of a compound machine comprising a multiple unit construction.

Fig. 4 is an end elevation of the same.

Fig. 5 is a vertical transverse section through one of the units.

Like numerals refer to like elements throughout the drawings in which 10 indicates generally my compound machine comprising a battery of units 11, shown in detail in Fig. 5, for example, same comprising a table 11^a carried by a plunger 11^b reciprocally mounted in the cylinder 11^c in the base of which is located the valve chamber 11^d. Inserted in this valve-chamber is a valve block 11^e provided with the inlet and duct 11^f communicating with the passage 11^g,

which in turn communicates with the duct 11^h which leads to the tube 11ⁱ to the inlet port 11^j in cylinder wall, from whence it leads to the clearance space beneath the plunger. Surrounding the passage 11^g is the valve seat 11^k and co-acting therewith is a valve 11^l shown in Fig. 5 as located in open position and a by-pass 11^m leading there beneath from the inlet port 11^j. Valve 11^l has its stem projecting upwardly beneath the striker block 11ⁿ carried by the plunger 11^b. An outlet port 11^p is located in the wall of the cylinder 11^c above the inlet port 11^j. This construction is similar to that shown and described in the patent to Mumford and Huggins, No. 1,167,511, and utilizes what is known as the Mumford-Huggins valve, the action being briefly as follows: Air or other operating fluid is admitted through the passage 11^g, with the valve 11^l in position shown. The air will flow through tube 11ⁱ beneath the plunger 11^b, operating to raise the latter until the portion 11° of the plunger cuts off the inlet port 11^j, at which time the momentum of the plunger and associated mechanism, as well as the expansive action of the operating fluid, will operate to carry the plunger up until the port therein communicates with the outlet port 11^p of the cylinder whereupon a large portion of the operating fluid acting against the plunger 11^b will exhaust through the port 11^p. Previous to cutting off the inlet port, the pressure on the lower side of the valve 11^l is less than that upon the upper side, which difference in pressure, as nearly as can be ascertained, is probably due to the flow of the operating fluid past the mouth of the duct 11^m, and this difference in pressure coupled with the weight of the valve serves to maintain the latter in the position shown in Fig. 5, or open position, as it is termed. After cutting off of the operating fluid takes place the back pressure is set up in the line and communicates with the under-side of the valve 11^l through the duct 11^m, whereby the pressures on the top and bottom of the valve are approximately balanced. Owing to the larger effective area on the bottom of the valve, its pressure operates to quickly move the valve to closed position. As the plunger and table move by their momentum and the expansive action of the confined air or the fluid upwardly, the port in the plunger 11^b communicates with the exhaust duct 11^p, 110

permitting the exhaust of the confined operating fluid, after which exhaust the plunger will drop to position shown in Fig. 5, whereupon the striker 11^a will contact with the top 5 of the valve stem and positively move the valve to open position.

It will be obvious that to construct an individual machine capable of handling large work it will require an extremely heavy 10 structure which would increase the cost of operation very greatly, such machines being practical only for use with special heavy work. To overcome these objects and economize shop operation, I provide a plurality or battery of individual units 11 mounted in alignment, as shown in the drawings, having their major axes co-axial. Rigid bars or beams 12 extend across, between and are secured to each side of the 20 units 11, being secured thereto by detachable bolts 12^a, or the like. An inlet manifold 13 is provided having branches 13^a communicating with each of the inlet ducts 11^a of the units 11, suitable stop-cocks or valves 25 13^b being provided for each of the branches 13^a. The main inlet, or supply pipe, 14 is provided with a suitable valve 14^a to control flow of fluid to manifold 13. It will be obvious that the entire supply of air may be 30 cut off or regulated by means of the valve 14^a, or the supply for any of the units 11, may be controlled by the individual valves 13^a, such regulation being advisable in handling some species of work.

35 I also provide an exhaust manifold 16 having branches 16^a communicating with the exhaust ports 11^b of the individual units 11. Valves, or the like 16^b are provided for each of the branches 16^a, and a 40 main exhaust pipe 17 is provided leading from the manifold 16 and provided with a controlling valve 17^a. As in the case of the supply, the individual exhaust ducts are separately regulatable by means of the 45 valves 16^b or the exhaust from the battery of machines may be controlled by the use of the valve 17^a. In this way, I am not only enabled to control the separate supply and exhaust of the operating fluid to meet the 50 conditions of operation, but I may simultaneously regulate both exhaust and supply of the battery.

It will be obvious while I have shown 55 three machines constituting the battery or compound machine, I may utilize shorter connecting or coupling bars 12, which I find desirable to use, or I may remove the bars 12 entirely and operate the units 11 independently.

60 In Fig. 3, I have shown the battery as located in a pit 18 having the floor 18^a thereon approximately adjacent to the level of the tables 11^a.

For the use of this compound machine, I 65 am enabled to present a large operating

table surface without having to increase the weight of the machines as would be the case in an individual machine of equal capacity. This, as stated above, reduces the amount of operating fluid used, permits me to increase 70 the frequency of the jolting portions and greatly reduces the cost of operation. In addition, it enables me to use the machines for small work or large work as desired, whereas in the present day practice it is 75 customary to allow the large capacity machines to remain idle when not handling large work.

The advantage of providing exhaust regulating valves lies in the fact that I am enabled to readily regulate the jolting or impact obtained, as it will be obvious that this impact will vary according to the amount of fluid exhausted from the working cylinder or rather according to the amount 80 of air remaining in such cylinder and resisting the impact.

It will be obvious that I may vary the construction shown and described in a number of ways to obtain same, and I do not 90 wish to be restricted to the form of my invention shown and described beyond the scope of the appended claims.

What I claim is:

1. A compound jolt ramming machine 95 comprising a plurality of separably operable unit machines comprising tables, and means for reciprocating said tables, means to directly and rigidly secure said tables together, and means to control the supply of 100 operating fluid to said machines.

2. A compound jolt ramming machine, comprising a plurality of separably operable unit machines comprising tables, and means for reciprocating said tables, means to 105 directly and rigidly secure said tables together, and means to control the exhaust of operating fluid from said machines.

3. In a machine of the class described, comprising a plurality of unit jolt ramming 110 machines, means to detachably and rigidly secure said machines together, means to supply operating fluid thereto, and a single means to separately control the exhaust from said units.

4. In a machine of the class described, comprising a plurality of unit jolt ramming machines, means to detachably and rigidly secure said machines together, means to supply operating fluid thereto, means to separately control the exhaust from said units, and a single means to simultaneously control the supply of operating fluid to said units. 115

5. In a machine of the class described, comprising a plurality of unit jolt ramming 120 machines, comprising tables, and means for reciprocating said tables, means to detachably and rigidly secure said tables together, means to supply operating fluid to said reciprocating means, means to separately con- 125 130

trol the exhaust from said units, and means to simultaneously control the exhaust from all said units.

6. In a machine of the class described, comprising a plurality of unit jolt ramming machines each having a table, and means to detachably and rigidly secure said tables together, said means comprising bars detachably secured to the tables of said units.

10 7. In a machine of the class described, comprising a plurality of unit jolt ramming machines, means to detachably secure said machines together, and an exhaust manifold having branches communicating with each of said units, said branches being each provided with a separately operable valve member.

8. A molding machine comprising a plurality of duplicate unit machines each com-

prising a cylinder, a plunger, means for admitting fluid pressure to the cylinder, a movable table controlled by said cylinder and plunger, said units being arranged with their tables adjacent to provide a larger table having the desired aggregate area, with a clearance between adjacent tables, means for locking two or more of said tables together to insure synchronous movement thereof, and means for supplying fluid pressure to all of the units thus connected to operate the individual tables as a single table or to operate the tables independently of each other when disconnected from each other.

In testimony whereof, I have subscribed my name.

PHILETUS W. GATES.
